US00D716841S

(12) **United States Design Patent**
Allyn

(10) **Patent No.:** **US D716,841 S**
(45) **Date of Patent:** **** Nov. 4, 2014**

(54) **DISPLAY SCREEN WITH ANNOTATE FILE ICON**

(75) Inventor: **Robert Allyn**, Pacific, MO (US)

(73) Assignee: **Covidien LP**, Mansfield, MA (US)

(**) Term: **14 Years**

(21) Appl. No.: **29/431,448**

(22) Filed: **Sep. 7, 2012**

(51) LOC (10) Cl. **14-04**

(52) U.S. Cl.

USPC **D14/495**; D14/490

(58) **Field of Classification Search**

CPC G06F 19/3437

USPC D14/485-495; D20/25, 31-33

See application file for complete search history.

CLAIM

The ornamental design for a display screen with annotate file icon, as shown and described.

DESCRIPTION

FIG. 1 is a front view of a display screen with annotate file icon; and,

FIG. 2 is a front view of a display screen with annotate file icon showing an alternative embodiment.

The broken line in the drawings illustrates a portion of the display screen which forms no part of the claimed design.

1 Claim, 1 Drawing Sheet
